[57] CLAIM

The ornamental design for an upper body thermal blanket, as shown and described.

DESCRIPTION

FIG. 1 is a top plan view of an upper body thermal blanket illustrated in an uninflated condition in accord with our new design;

FIG. 2 is a bottom plan view of the upper body thermal blanket shown in FIG. 1;

FIG. 3 is a side elevational view of the blanket of FIG. 1 illustrated in an inflated condition as taken from the lower edge of FIG. 1;

FIG. 4 is a side elevational view of the blanket as taken from the upper edge of FIG. 1, the blanket being illustrated in the inflated condition; and,

FIG. 5 is an end view of the blanket of our design as taken from the right end of FIG. 1, the blanket being shown in the inflated condition, the opposite end being similar thereto.
